UNITED STATES PATENT OFFICE.

EDWIN LEHMANN, OF PEORIA, ILLINOIS.

DESIGN FOR A BOTTLE.

46,683.

Specification for Design. Patented Nov. 24, 1914.

Application filed September 15, 1914. Serial No. 861,896. Term of patent 14 years.

To all whom it may concern:

Be it known that I, EDWIN LEHMANN, a citizen of the United States, residing at Peoria, in the county of Peoria and State of Illinois, have invented a new, original, and ornamental Design for Bottles, of which the following is a specification, reference being had to the accompanying drawing, forming part thereof.

Figure 1 is a side elevation of a bottle, showing my new design; and Fig. 2 is a bottom plan view thereof.

I claim—

The ornamental design for a bottle, as shown.

EDWIN LEHMANN.

Witnesses:

JOHN O'BRIEN,
BEN G. ROTH.
